UNITED STATES PATENT OFFICE

FRITZ HEINEMANN, OF HAMBURG, GERMANY

RAILWAY-TRACK CONSTRUCTION

Application filed September 17, 1929, Serial No. 393,284, and in Germany September 25, 1928.

This invention relates to a railway track construction with unpierced iron transverse sleepers and has for its object to provide a simple method of fixing the rails upon the sleepers both for the normal gauge of track and also for the increased gauges corresponding to bends in the track. The improved method of fixing is also required to safely transmit through ample surfaces all forces acting between rails and sleepers in the different directions, particularly the transverse forces acting horizontally in the longitudinal direction of the sleeper which occur between rails and sleepers, in contradistinction to the known rail fixing devices with which the transmission of the transverse forces takes place at the edges of the holes in the sleeper covers.

These known rail fixing devices have the disadvantage that on account of the smallness of the contact surface between the edges of the holes, on the one hand, and the bolt shank or the hook of the hook plate, on the other hand, rapid wear takes place which is still further increased by the circumstance that with the putting together of the track a certain amount of play must be present between edges of the holes and bolt shanks or hooks, which play from the beginning prevents a satisfactory contact of the surfaces and therewith leads to the loosening and rapid wearing out of the parts. A further disadvantage of the known arrangement is that, corresponding to the gauge of the track at curves, the holes which serve for securing the two rails must have a correspondingly greater distance from one another, and that consequently a greater number of different sleepers must be prepared and held in stock.

The invention consists herein, that the sleepers are provided with teeth arranged side by side in the longitudinal direction of the sleepers, and that the parts serving for fixing the rails upon the sleepers at their points of contact with the sleepers are likewise provided with teeth which can be brought selectively into engagement with the teeth of the transverse sleepers corresponding to the desired gauge of track. Preferably the teeth of the transverse sleepers are ar-

ranged upon surfaces sloping downwardly from the outer edges of the transverse sleepers and inwardly directed.

According to the invention the parts serving for fixing are adapted to transmit to the said sloping surfaces both the horizontal counter-forces corresponding to the pressure of the rails upon the surfaces of the sleepers and also the horizontal forces occurring in the direction of the rails between rails and sleepers, while the horizontal forces occurring (in the longitudinal direction of a sleeper) between rails and sleeper are taken up by the teeth of the sleepers.

The invention is illustrated in four constructional examples in the accompanying drawings.

In the constructional example shown in Figs. 1-7;

Fig. 1 is a cross-section through the rail on the lines 1-1 of Fig. 2;

Fig. 2 is a side view of the rail on the sectional line 2-2 of Fig. 1;

Fig. 3 is a sectional plan corresponding to Fig. 1 on the line 3-3 of Fig. 1;

Fig. 4 is a sectional plan corresponding to Fig. 2 as seen from below on the line 4-4 of Fig. 2;

Fig. 5 is a side view of a fixing bolt drawn to an enlarged scale;

Fig. 6 is a plan corresponding to Fig. 5;

Fig. 7 is a section on the line 7-7 of Fig. 2 drawn to an enlarged scale.

Fig. 8 is a cross-section through the rail on the line 8-8 of Fig. 9.

Fig. 9 is a sectional side view of the rail on the line 9-9 of Fig. 8.

Fig. 10 is a sectional plan corresponding to Fig. 8 on the line 10-10 of Fig. 8.

Fig. 11 is a section on the line 11-11 of Fig. 8.

Fig. 12 is a cross-section through the rail on the line 12-12 of Fig. 9, drawn to an enlarged scale.

Fig. 13 is a cross section through the rail on the line 13-13 of Fig. 14;

Fig. 14 is a sectional side view of the rail on the line 14-14 of Fig. 13;

Fig. 15 is a cross-section through the sleeper in the non-stressed condition;

Fig. 16 is a sectional plan corresponding to Fig. 13 on the line 16—16 of Fig. 13;

Fig. 17 is a sectional plan seen from below corresponding to Fig. 14 on the line 17—17 of Fig. 14.

5 Fig. 18 is a section on the line 18—18 of Fig. 14 drawn to an enlarged scale;

Fig. 19 is a side view of the bow corresponding to Fig. 13, drawn to an enlarged scale.

10 Fig. 20 is a plan corresponding to Fig. 19.

Fig. 21 is a cross section through the rail on the line 21—21 of Fig. 22;

Fig. 22 is a sectional side view of the rail 15 on the line 22—22 of Fig. 21;

Fig. 23 is a cross-section through the pair of sleepers *b* *b* in non-stressed condition;

Fig. 24 is a sectional plan on the line 24—24 of Fig. 21;

20 Fig. 25 is a sectional plan seen from below corresponding to Fig. 22, taken on the line 25—25 of Fig. 22;

Fig. 26 is a section on the line 26—26 of Fig. 22 drawn to an enlarged scale.

25 Referring to Figures 1—7, *a* is a rail of the track, *b* an iron transverse sleeper which in the constructional example illustrated has a T-shaped cross-section. The sleeper *b* is provided on both sides with sloping surfaces *b'* which slope downwardly from the outer edges of the sleeper and are inwardly directed. On one of the two sloping surfaces (that shown on the left in Fig. 2) teeth *b*² are arranged parallel, these teeth being provided at 30 the place at which (for the occurring gauges of track) the rails are fixed upon the sleepers. The teeth *b*² are preferably formed by being rolled-in into the sloping surfaces. They may also be rolled-in over the entire 35 length of the sleeper into the one sloping surface (or into both sloping surfaces). *c* is a supporting plate the length of which in the direction of the rails is greater than the width of the sleeper, and the breadth of which in the direction of the sleeper is greater than the breadth of the rail foot. The plate *c* has 40 flanges *c'* and *c*² projecting downwardly over the edges of the sleeper. The flange *c'* can be pushed with its corresponding sloping surface into engagement with the surface *b'*. The flange *c*² carries a surface sloping downwardly and outwardly directed, which, when the flange *c'* is pushed into engagement with the one sloping surface *b'*, is removed a short 45 distance from the other sloping surface *b'* and likewise is provided with teeth *c*³. The supporting plate *c* has, further, upwardly projecting flanges *c*⁴ and *c*⁵. The flange *c*⁵ engages over the rail foot, the flange *c*³ carries at a distance from the rail foot a surface 50 sloping upwards and outwardly directed. The fixing of the sleeper to the rail is effected by means of three bolts *e*, *f*, and *g*. The bolts *e* and *f* which are similar to one another 55 have heads *e'* or *f'* of trapezium-form in cross-

section, of which the sloping side surfaces are provided with teeth *e*² or *f*². *d*, *d* are wedge-shaped supporting plates which are pushed over the bolts *e* and *g*, and abut with the one wedging surface on the rail foot and the other 70 wedging surface on the sloping surface *c*⁶.

On tightening the nuts *e*³, *f*³, *g*³ the supporting plate *c* is pushed with the flange *c'* solid against the one sloping surface *b'* of the sleeper *b*, the rail *a* is pressed with its rail foot solid upon the flange *c*⁴ of the supporting plate engaging thereover, and the rail *a* is pressed solid upon the supporting plate *c*, which again is pressed solid upon the sleeper *b*.

80 Referring to Figs. 8—12 *a* is a rail of the track, *b* an iron transverse sleeper which is of the hollow kind in the constructional example illustrated. The sleeper *b* is provided on its upper surface with laterally projecting flanges which have toothed surfaces *b*² sloping downwards from their outer edges and inwardly directed. Upon the edges of the sleeper *b* two bow-shaped supporting plates *h* are laid under the rail foot, each of which has a toothed flange *h*¹ extending laterally over the edge of the sleeper and projecting downwards and engaging in one of the two toothed parts *b*² of the sleeper. Further each bow-shaped supporting plate *h* has on both sides 90 of the rail upwardly projecting hook-shaped flanges *h*² and *h*³. The flange *h*² abuts upon the rail foot and has a passage opening *h*⁴ for a screw bolt. The other flange *h*³ is provided at a distance from the rail foot with a plain 95 inwardly sloping and downwardly directed surface. Between this surface and the rail foot a wedge *k* provided with a boring can be pushed. Through the passage openings *h*⁴ of the two bows *h* a screw bolt *n* is passed and through the borings of the two wedges *k* a screw bolt *m* is passed which can be tightened 100 up by means of nuts *n'* and *m'*. By tightening the nuts *n'* and *m'* the two supporting plates *h* are simultaneously pressed with 105 their toothed flanges *h*¹ against the toothed sloping surfaces *b*² of the sleeper *b*, the rail *a* is pressed against the flange *h*² of the supporting plate *h* and the rail is also pressed vertically downwards upon the supporting 110 plate and the latter upon the sleeper. 115

120 Referring to Figs. 13—20, the rail *a* is laid immediately upon the sleeper *b* which in the constructional example illustrated has a T-shaped cross-section. The sleeper *b* is provided on both sides with sloping surfaces *b'* which are directed downwardly and inwardly sloping from the outer edges of the sleeper. At the places at which (for the occurring 125 gauges of track) the rails are fixed upon the sleepers, teeth *b*² located parallel are arranged upon the sloping surfaces *b'*. *i*, *i* are two bows laid under the rail foot on both sides near the sleeper, which bows have a lateral toothed portion *i'* engaging in the teeth *b*² of 130

the abutting surface b' . Each of the two iron bows i has two upwardly projecting hook-shaped flanges i^2 and i^3 . The hook-shaped flange i^2 engages over the rail foot. The hook-shaped flange i^3 carries at a short distance from the rail foot a surface i^4 inwardly sloping and downwardly directed. Between this surface and the rail foot a wedge k provided with a boring can be pushed. Through the hooks i^2 of the two bows i a screw bolt n is passed and through the borings of the two edges k a screw bolt m is passed, which bolts can be tightened by means of nuts n' and m' . By tightening the nuts n' and m' the rail a is pressed against the sleeper b and simultaneously the iron bows i are pressed with their toothed portions i^2 against the toothed sloping surfaces b^2 of the sleeper b and the foot of the rail a is pressed against the hook-shaped 20 flange i^2 of the bow i .

The top carrier flange of the T-shaped sleeper may, as seen in Fig. 15, have the curved form in the nonstressed condition, and only be stressed into the flat form shown in 25 Fig. 14 by tightening the nuts n' and m' . The tension thus produced conduces to maintaining the tension in all the connections.

Referring to Figs. 21-26, in the constructional example shown herein the rail a is fixed 30 upon a supporting plate p and this is fixed upon two sleepers b, b arranged in pairs at a short distance from one another. The two sleepers b, b are provided on their outer edges with sloping surfaces b^1, b^1 which are directed 35 sloping downwards and inwardly, and at the places where the rails are fixed upon the sleepers (for a given gauge of track) are provided with teeth b^2 arranged parallel in the longitudinal direction of the sleepers. At their inner edges both sleepers b, b are provided with 40 surfaces b^3, b^3 sloping downwards and outwardly directed. p is a supporting plate the length of which in the direction of the rails is greater than the total breadth of both sleepers. The toothed portions of the flanges p' 45 projecting downwardly over the sleeper edges engage in the toothed portions b^2, b^2 of the two sleepers. The supporting plate p has also on one side near its end two upwardly directed flanges p^2, p^2 with which it embraces the rail foot and on the other side in the middle portion a widening p^3 which is provided 50 with a plain flange p^4 sloping upwards and outwardly. The rail is pushed upon the supporting plate p against the flanges p^2 . Then a wedge piece o is inserted which abuts with its one sloping surface against the rail foot and with its other sloping surface against the flange p^4 . Below this wedge piece an intermediate member s formed wedge-shaped inwardly and outwardly is laid with its outer sloping surfaces against the sloping surfaces b^3, b^3 of the sleepers. Then a bolt r is pushed 55 through corresponding borings of the intermediate member s and the wedge piece o and

by means of the nut r' the wedge-shaped head r^2 is pressed against the intermediate member s .

By tightening up the nut r' the two sleepers are pressed away from one another at 70 their upper parts and their inclined toothed portions are pressed into the toothed portions of the flanges p' ; further the rail foot is pressed solid against the flanges p^2 , the rail is pressed solid upon the supporting plate p , 75 and the latter is pressed solid upon the two sleepers b .

The top carrier flanges of the two sleepers may, as seen in Fig. 23, have the curved form in the non-stressed condition and only be 80 stressed into the flat form shown in Fig. 22 by tightening the nut r' .

The constructional forms shown in Figs. 1-7, Figs. 8-12, Figs. 13-20, are also adapted for use with the transverse sleepers bedded 85 into a concrete foundation.

Also with all constructional forms rails with the usual cross-sectional form may be used instead of rails of the kind having a sloping away foot. 90

I claim:—

1. Railway track construction comprising in combination iron transverse sleepers having downwardly and inwardly sloping surfaces, a series of parallel teeth arranged on 95 said surfaces in the longitudinal direction of the sleeper, a clamping member for clamping the rail foot in position upon the sleeper and a series of teeth on said clamping member adapted to engage with the teeth on the 100 sleeper when in clamping position.

2. Railway track construction comprising in combination, iron transverse sleepers having downwardly and inwardly sloping surfaces, series of parallel teeth arranged on 105 said surfaces in the longitudinal direction of the sleeper at the places at which the rails are to be fixed upon the sleepers, a clamping member for clamping the rail foot in position upon the sleeper, and series of teeth on 110 said clamping member adapted to be brought selectively into engagement with the teeth of the sleepers corresponding with the desired gauge of track.

3. Railway track construction, comprising 115 in combination iron transverse sleepers having downwardly and inwardly sloping surfaces, a series of parallel teeth arranged on said surfaces in the longitudinal direction of the sleeper at the places at which the rails are to be fixed upon the sleepers, a clamping member for clamping the rail foot in position upon the sleeper and a series of teeth on 120 said clamping member adapted to be brought selectively into engagement with the teeth of the sleepers, the clamping member transmitting to the said sloping surfaces both the vertical counter-forces corresponding to the pressure of the rails upon the surface of the sleepers and the horizontal forces occurring 125 130

in the direction of the rails between rails and sleeper, while the horizontal forces occurring in the longitudinal direction of the sleeper between rail and sleeper are taken up by the toothed parts on said sloping surfaces of the sleeper in the teeth of which the teeth of the clamping member engage.

4. Railway track construction according to claim 3, in which the rails are secured upon two sleepers laid in pairs a short distance apart, each of which is provided on both sides with sloping surfaces directed downwardly and inwardly; in combination with a supporting plate which has inwardly directed toothed hook-shaped flanges projecting downwardly over the outer edges of the two sleepers and engaging in the toothed portions of the two sleepers, and also having two upper hook-shaped flanges arranged near the outer sleeper edges and engaging the rail foot upon one side, and upon the other side of the rail having at a short distance from the rail foot a central flange provided with an upwardly sloping and outwardly directed surface, a wedge parallel to the sleepers and located below the supporting plate abutting against the inner sloping surfaces of the sleepers, and a wedge located above the supporting plate and parallel to the rail, engaging on one side against the rail foot and on the other side against the said sloping surface of the central flange, and a screw-bolt connecting the two wedges and forcing the abutting surfaces together.

FRITZ HEINEMANN.
